OR 0 14,987

No. 14,987

May 6, 1884

UNITED STATES PATENT OFFICE.

ISAIAH G. HATCHER, OF CLEVELAND, OHIO.

DESIGN FOR A BURIAL-CASKET.

SPECIFICATION forming part of Design No. 14,987, dated May 6, 1884.

Application filed February 11, 1884. Term of patent 7 years.

To all whom it may concern:

Be it known that I, ISAIAH G. HATCHER, a citizen of the United States, residing at Cleveland, in the county of Cuyahoga and State of Ohio, have invented and produced a new and original Design for Burial-Caskets, of which the following is a specification, reference being had to the accompanying drawing, forming part thereof.

10 Figure 1 is a side elevation of my newly-designed burial-casket.

I have invented and produced a new design in burial-caskets, the same being provided with what is known as a "raised cover," in which the raised work is brought forward and terminates at the edge of the cover, so as to have no ledge or margin on the cover, and bounded by a single curved line, as shown, broken only by slight fillets, to relieve the 15 sameness of the curved line. The bottom portion of the casket is encircled by a broad molding, the peculiar features of which are its undulating swells and depressions running cross-wise of the molding and gradually decreasing

in depth, but retaining their width as they approach the upper edge of the molding, as shown in the drawing.

What I claim is—

The design for a burial-casket herein shown and described, the same consisting of a cover with raised work that is brought forward so as to be flush with the edge of the cover, and sweeping down from the top to the bottom of the raised work in a single curve, as shown, and the casket encircled at the bottom by a broad molding ornamented with swells and depressions that run crosswise of the molding, and that become less in depth, but retain their width as they approach the top of the molding, substantially as shown and described. 40

In testimony whereof I hereunto set my hand, in the presence of two subscribing witnesses, this 2d day of February, A. D. 1884.

ISAIAH G. HATCHER.

Witnesses:

CHAS. H. DORER,
ALBERT E. LYNCH.
